United States Patent Office

Des. 230,857
Patented Mar. 19, 1974

230,857

DESK CALCULATOR

George J. Lampel, Los Angeles, Calif., assignor to Citizen America Corporation, Beverly Hills, Calif.

Filed Nov. 2, 1972, Ser. No. 303,211

Term of patent 14 years

Int. Cl. D14—02

U.S. Cl. D26—5 C

F D 9.1

F D 9.2

FIG. 1 is an isometric view of a desk calculator showing my new design;

FIG. 2 is a front elevational view thereof;

FIG. 3 is a top plan view thereof;

FIG. 4 is a right side elevational view thereof; and

FIG. 5 is a rear elevational view thereof.

I claim:

The ornamental design for a desk calculator, as shown.
